UNITED STATES PATENT OFFICE.

ELIJAH A. SUTHERLAND, OF CARIBOU, MAINE.

PRESSURE GAUGE.

Application filed February 4, 1926. Serial No. 85,973.

The present invention relates to improvements in pressure gauges for use in connection with the inflating valve of an inner tube, which is associated with a pneumatic tire.

One of the important objects of the present invention is to provide a gauge which is of such construction as to enable the air pressure within the inner tube to be readily and easily ascertained without necessitating the removal of the cap from the valve stem, such as must now be done where an independent pressure gauge is used.

A further object is to provide a pressure gauge of the above mentioned character which is simple in construction, inexpensive, strong and durable, and further well adapted to the purpose for which it is designed.

Other objects and advantages of this invention will become apparent during the course of the following description taken in connection with the accompanying drawing.

In the accompanying drawing forming a part of this application, and in which like numerals designate like parts throughout the same:

Figure 1 is a central longitudinal sectional view through the pressure gauge embodying my invention showing the same attached to the ordinary valve stem, and

Figure 2 is a side elevation of the cap or casing.

In the drawing, wherein for the purpose of illustration is shown the preferred embodiment of my invention, the numeral 1 designates the substantially cylindrical casing or cap, the upper end of which is closed, the lower portion of the cap or casing 1 is enlarged as indicated at 2 whereby a shoulder 3 is formed at the juncture of the enlarged portion 2 and the adjacent portion of the cap or casing. The purpose of the shoulder will be hereinafter more fully described.

The lower portion of the enlarged portion 2 is internally threaded so that the cap or casing may be threaded on the valve stem 4 which is of the usual construction and is associated with the inner tube in the usual manner. The valve which is mounted in the valve stem 4 is also of the usual construction, and is indicated at 5.

The cap or casing 1 is provided at spaced intervals with the longitudinally extending slots or sight openings 6 and placed on the outer face of the casing directly adjacent

the side edges of the respective slots are the graduations or scale marks indicated at 7.

Arranged within the lower portion of the cap or casing 1 is the expansible air pocket 8 which is formed preferably of rubber; the open lower end of said air pocket extends downwardly into the enlarged portion 2 of the cap or casing 1 and is vulcanized to the inner peripheral face of the metallic ring 9, the latter being adapted to fit snugly within the enlarged portion 2 and being further adapted to abut the shoulder 3 in the manner as clearly shown in Figure 1 so that the expansible air pocket will be maintained in proper position within the cap or casing.

This expansible air pocket is preferably arranged in such a manner as to extend directly over the upwardly projecting portion of the valve 5 so that when the valve 5 is moved downwardly in the manner hereinafter to be more fully described, the air which escapes from the inner tube through the valve will enter the pocket 8 and cause the same to expand.

Adapted for slidable movement within the cylindrical casing or cap 1 is the indicator member 10, the same being in the form of a disc and having a preferably red colored line 11 extending circumferentially therearound so that the same may be readily and easily visible through the sight opening or slot 6.

An expansible coil spring 12 is arranged within the casing or cap 1 and is disposed between the closed upper end of the cap 90 and the upper face of the indicator member 10 so as to normally force the indicator member 10 downwardly into engagement with the closed upper end of the expansible air pocket or chamber 8. This construction is clearly illustrated in Figure 1.

A bracket 13 is secured at its lower end to the inner wall of the enlarged portion 2 of the casing or cap 1 and this bracket extends upwardly into the air pocket 8 and is then disposed laterally and thence downwardly and carries on the free end thereof the valve engaging head 14.

When the cap is threaded downwardly on the valve stem a sufficient distance in order to permit the head 14 to engage the valve 5 and move the same downwardly, a certain amount of the air in the inner tube will escape out through the valve stem and will enter the pocket 8, and will cause the

latter to expand and simultaneous with the expansion of the air pocket, the indicator member 10 will move upwardly against the tension of the coil spring 12 so that the exact amount of air pressure within the pneumatic tire may be readily and easily ascertained by glancing at the red line 11 on the indicator member 10 through any of the sight openings 6, the graduations on the outer face of the cap enabling the exact air pressure to be ascertained. This will enable the operator of the vehicle to at all times know the exact amount of air which is in each of the tires.

15 Whenever it is necessary to inflate the pneumatic tire, the cap may be easily removed, and the inner tube inflated in the usual manner.

20 The provision of a pressure gauge of the above mentioned character will save considerable time and labor in ascertaining the amount of air contained within a pneumatic tire and furthermore the use of a separate or independent pressure gauge will be eliminated.

25 While I have shown the preferred embodiment of my invention it is to be understood that minor changes in the size, shape, and arrangement of parts may be resorted to without departing from the spirit of the invention and the scope of the appended claims.

30 Having thus described the invention, what I claim as new and desire to secure 35 by Letters Patent is:—

35 1. A pressure gauge comprising a cylindrical casing closed at its upper end, the lower end of the casing being enlarged, said enlarged end adapted to be threaded on the 40 pneumatic tire valve stem and normally spaced from the base thereof, an expandible air pocket arranged within the casing directly over the valve in the upper end of the valve stem, a retaining ring secured to the 45 lower open end of the air receiving pocket, said ring being fitted in the enlarged portion of the casing, an indicator member

operable within the upper portion of the casing, an expandible coil spring disposed between the closed upper end of the casing 50 and the upper face of the indicator member for normally holding the latter in engagement with the upper closed end of the air pocket, a bracket secured on the inner side of the enlarged portion of the casing and 55 extending upwardly into the air receiving pocket, a head formed on the free-end of the bracket and disposed directly above the valve stem and normally in engagement with the valve to permit the escape of the 60 air from the pneumatic tire into the expandible air pocket whereby the indicator member is actuated when the casing is moved downwardly on the valve stem.

2. A pressure gauge comprising a cap 65 closed at its upper end, the open lower end thereof being adapted to be threaded on the usual pneumatic tire valve stem and being enlarged, the lower end of the cap being normally spaced from the base of the valve 70 stem, said cap being provided with a series of longitudinally extending annular spaced sight openings, an expandible air pocket arranged within the cap directly over the valve in the valve stem, a retaining ring secured to the lower open end of the air receiving pocket, said ring being fitted in the enlarged portion of the cap, an indicator member operable within the upper portion of the cap, an expandible coil spring disposed between the closed upper end of the cap and the upper face of the indicator member for 80 normally holding the latter in engagement with the upper closed end of the air receiving pocket, and means carried by the cap for actuating the valve in the valve stem to permit the air to escape from the pneumatic tire through the valve into the air receiving pocket whereby said indicator member may be actuated when the cap is threaded downwardly on the valve stem.

45 In testimony whereof I affix my signature.

ELIJAH A. SUTHERLAND.
